No. 767,767.

PATENTED AUG. 16, 1904.

J. RUEGG,

RAIL VALISE.

APPLICATION FILED SEPT. 4, 1903.

NO MODEL.

UNITED STATES PATENT OFFICE.

JACOB RUEGG, OF STIRLING, NEW JERSEY.

RAIL-VALISE.

SPECIFICATION forming part of Letters Patent No. 767,767, dated August 16, 1904.

Application filed September 4, 1903. Serial No. 171,996. (No model.)

To all whom it may concern:

Be it known that I, JACOB RUEGG, a citizen of the United States, residing at Stirling, in the county of Morris and State of New Jersey, 5 have invented certain new and useful Improvements in Rail-Valises, of which the following is a specification.

This invention provides a peculiar form of carrier more especially adapted for transporting the warp beam or spool used upon looms from place to place after the thread has been wound thereon. The article above constituted must be very delicately handled, since it is very necessary that the silk threads be thoroughly protected, and for this reason it is usually boxed or crated preparatory to transportation.

It is therefore an essential object of my invention to secure an efficient substitute for the ordinary method of packing the "warps," which is more conveniently applicable, more economical owing to the fact that it may be used over and over again, and which, further, is lighter than a box or crate, thereby involving a decreased amount of cost relative to transportation.

For a full description of the invention and the merits thereof and also to acquire a knowledge of the details of construction of the means 30 for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a view showing my valise or carrier applied thereto. Fig. 2 is a plan view of 40 the valise open. Fig. 3 is an end view of my invention. Fig. 4 is a modification showing a different form of body. Fig. 5 is a detail view of the securing means alone.

Corresponding and like parts are referred 45 to in the following description and indicated in all the views of the drawings by the same reference characters.

The valise is a simple construction comprising a body 1, which is preferably made of 50 sheet material—such as canvas, leather, or the

like—which is adapted to encircle the warp-beam, which is designated 2, embracing the latter. The warp-beam, which carries the thread, is of ordinary form, flanged at the corresponding end portions, as shown at 3, and 55 provided with the journals 4. The valise encloses the warp-beam, and in order to secure the device about the beam any suitable means, such as buckles 5 and coöperating straps 6, may be employed. The corresponding end 6c portions of the body 1 of the valise or carrier are provided with a series of openings 7, disposed at intervals thereon, and these openings receive draw-strings 8, which, passing therethrough, are adapted to draw the ends about 65 the beam 2 to prevent lateral displacement of the carrier and for the protection of the threads in a manner very clearly seen. The protector bars or slats 10 are secured to the straps 6 longitudinally, being spaced from 70 each other, so as to not only protect the valise is usage, but also to serve as stiffening means for the article.

The bars or slats 10, together with the straps 6, to which they are attached, are entirely independent of the body of the valise and, as shown, are secured to the longitudinal straps 6 or like elements by suitable fastenings, so as to be separately applied to the body 1 after the same has been disposed so as to embrace 80 the warp-beam preparatory to the transportation of the latter.

It will be understood that within the contemplation of my invention I may substitute chains or any equivalent means for the straps 85 6, which carry the bars 10 when the latter are independently used.

The valise or carrier may be very cheaply constructed, and after the warp-beam has been transported the carrier is removed therefrom 90 and may then be returned to the original sender of the beam or reused in any manner as found desirable.

It is my design to utilize the general construction of the carrier embodied in my invention for other purposes than transporting warp-beams, since, as would be obvious, same may be made in different sizes for use as a shipping-trunk or like receptacle.

In the modified form of the invention shown 100

in Fig. 4 of the drawings a carrier more especially adapted for transporting bolts of cloth is illustrated, same being of approximately oblong form when filled. This carrier comprises the body 1, provided with securing means having the stiffener-bars 10 in like manner as the preferred form of the valise.

Having thus described the invention, what is claimed as new is—

10. In a valise or carrier for transporting warp-beams or the like, the combination of a body of sheet material adapted to embrace the article to be carried thereby, removable securing

means for said body comprising removable straps, and paralleling stiffener protecting-bars permanently attached to the said straps securing the same together and adapted for removal upon displacement of the straps aforesaid.

In testimony whereof I affix my signature in presence of two witnesses.

JACOB RUEGG. [L. S.]
